COLLAR BUTTONS

Norman P. St. John, Arlington, Va.

Application November 27, 1953, Serial No. 394,628

1 Claim. (Cl. 24—101)

The present invention relates to a collar button for 15 use with shirts, collars and the like.

The button of the present invention is shaped as a solid of generally elliptical horizontal section and reduced in size inwardly from the top portion and from the base portion, the base portion and the top portion 20 having the form of an ellipse, the base portion being larger in a horizontal plane than the top portion. The base is curved slightly to conform to the neck of a wearer, while the top portion is convex.

It is an object of the present invention to provide a 25 collar button having a plurality of ridges and grooves, symmetrically arranged on the narrow end edges of the stem.

It is a further object of the invention to provide a collar button with means to prevent loss of the collar button 30 from a shirt.

A still further object of the present invention is the provision of a collar button, that will secure the collar of a shirt, or a collar to a shirt, or a tie to a shirt.

A still further object of the invention is the provision 35 of a collar button that is easy to insert in the button hole of a shirt, collar or the like.

The present invention can be used to good advantage with the shirt having attached collar disclosed in my U. S. Patent No. 2,659,891.

Other objects and advantages of the present invention are set forth in the specification and illustrated in the accompanying drawing in which:

Figure 1 is a perspective view of the collar button.

Figure 2 is a view of the collar button looking at one 45 vertical end of the shank or stem and showing the grooves and ridges.

Figure 3 is a top or plan view of the collar button, and

Figure 4 is a bottom view of the collar button.

Referring to the drawing the numeral 1 represents the 50 top of my improved collar button, 2 the stem and 3 the

2

base. The top 1 and base 3 are of substantially elliptical configuration, the base being curved to conform to the curvature of the neck of a wearer.

Interposed between the base 3 and the top 1 is a stem 5, that is provided on its end portions with one or more ridges 4 and grooves 5, and it is to be noted, that the stem is of tapered configuration, tapering from the bottom to the top, the sides of the stem being smooth.

From the description, it will be seen that I have provided a collar button that embodies a top, base and stem, all being of substantially elliptical configuration in shape about a common vertical axis, the stem being provided with a plurality of grooves for receiving collar button holes in shirts and collars, and a plurality of ridges for holding collar and shirt bands together, and also for supporting preformed ties having a hook that engages one of the plurality of grooves.

Changes in detail may be made without departing from the spirit of the invention.

I claim as my invention:

A collar button comprising a top, base, and connecting stem, the greatest horizontal section of the top, and base being substantially elliptical in shape, and the stem being substantially elliptical in any horizontal section thereof, the top, stem and base each being symmetrical about a common vertical axis, the greatest of the horizontal dimensions of the said top, stem, and base lying in a common plane through said axis, said stem having one or more portions thereof extending symmetrically outwardly therefrom, and lying in said common plane, each of said portions being adapted to coact with an adjacent extending portion or with the top or base to form a groove adapted to prevent a collar button from sliding out of a button hole in which said collar button is inserted, the width or dimension of the stem in a plane at right angles to said common vertical plane increasing from the end of the stem near the top to the end of the stem near the base.
